UNITED STATES PATENT OFFICE

EDWIN G. FRANCK, OF DETROIT, MICHIGAN, ASSIGNOR TO HUTCHINS CAR ROOFING COMPANY, OF DETROIT, MICHIGAN, A CORPORATION OF DELAWARE

CAR ROOF

Application filed November 21, 1927. Serial No. 234,794.

This invention relates to car roofs and more particularly to that type of roof in which metal roofing sheets are employed.

The invention relates more particularly to the connection between the substructure of the car and the roofing sheets at the eaves and has as its objects to simplify, render more efficient and improve generally constructions of this character.

10 The several objects, advantages and novel details of construction of this invention will be made more apparent as this description proceeds, especially when considered in connection with the accompanying drawings

15 wherein:

Figure 1 is a fragmentary top plan view of a car roof constructed in accordance with my invention, and

Figure 2 is an enlarged fragmentary sectional view taken substantially on the plane indicated by line 2—2 in Figure 1.

Referring now more particularly to the drawings wherein like reference characters indicate like parts it will be noted that there is illustrated a side plate 10 to which fascia plates 11 are connected by means of bolts 13 which also act to secure in place side sheathing 14. The sub-structure comprises carlines 15 and purlines 16 and the customary ridge 25 pole (not shown). The metal roofing sheets 17 are supported upon this sub-structure and are provided with upstanding side edge flanges 18, the joint between adjacent roofing sheets being covered and weather-proofed 30 by transverse caps 19 secured in place by means of bolts 20.

The eaves end of each roofing sheet is bent to form an inwardly extending portion or flange 21 terminating in an upwardly extending projection or flange 22. Extending under the inwardly bent portion of the roofing sheets is a main flashing strip 23. This flashing strip is provided with a return-bent portion 24 which extends back over the inwardly 40 extending portion 21 of the roofing sheets and terminates in a downwardly extending portion or flange 25. This downwardly extending flange 25 overlaps the upwardly extending flange 22 of the roofing sheet and acts 45 as a stop to oppose and limit outward move-

ment of the roofing sheet. This construction permits of a freedom of movement of the roofing sheets while preventing the same from moving outwardly away from the ridge of the car. The construction further permits 55 the flashing strips to move freely in an outward direction in consequence of a bowing of the side plates. The reference character 26 indicates flashing strips arranged at the joints of the main flashing strips 23.

The eaves end of each transverse cap 19 is provided with an inwardly bent portion 27 which extends within the space 28 between the inwardly bent portion 21 of the roofing sheet and flashing strip 23. This construction affords means for satisfactorily weather-proofing the joint between adjacent roofing sheets at the eaves. 60

While the invention has been illustrated as applied to steel frame cars it will be immediately apparent to those skilled in this art that it may be applied with equal facility to wood frame cars and furthermore that obvious changes and modifications in the specific details herein illustrated may be made as come 70 within the purview of the accompanying claims. 75

What I claim as my invention is:

1. In a car roof, the combination with a sub-structure, of a roofing sheet arranged thereover, the eaves end of said roofing sheet being bent to form an inturned portion terminating in an upstanding flange and a flashing strip having an extended area of engagement with said flange throughout its entire 80 length and acting as a stop to limit outward movement of said roofing sheet. 85

2. In a car roof, the combination with a sub-structure, of roofing sheets arranged thereover, the eaves end of each roofing sheet being bent to provide an upstanding flange and a flashing strip provided with a downwardly extending flange engaging said roofing sheet flange its entire length to limit outward movement of said roofing sheet. 90

3. In a car roof, the combination with a sub-structure, of a roofing sheet arranged thereover, the eaves end of said roofing sheet being bent to form an inturned portion terminating in an upstanding flange, and a 100

flashing strip extending under said inturned portion and over said flange and terminating in a downwardly extending flange engaging said upstanding flange throughout its length and constituting a stop to limit outward movement of said roofing sheet.

4. In a car roof, the combination with a sub-structure, of a roofing sheet arranged thereover, the eaves end of said roofing sheet being bent to form an inturned portion terminating in an upstanding flange and a flashing strip formed throughout its length with a return bent portion extending under and over said inturned portion, said return-bent portion terminating in a downwardly extending flange engaging said upstanding flange to limit the outward movement of said roofing sheet.

5. In a car roof, the combination with a sub-structure, of roofing sheets arranged thereover, the eaves ends of said roofing sheets being formed with inturned portions terminating in upstanding flanges, a flashing strip having a return bent portion extending under said inturned portions in spaced relation thereto and over said inturned portions, said return-bent portion terminating in a downwardly extending flange engaging said upstanding flanges and joint caps for the side edges of said roofing sheets having portions extending into the space between said inturned portions and flashing strip.

6. In a car roof, the combination with a sub-structure, of a roofing sheet arranged thereover, the eaves end of said roofing sheet being provided with an upstanding substantially vertical flange and a flashing strip formed throughout its length with a downwardly extending substantially vertical flange having an extended area of engagement with said upstanding flange, for the purpose described.

7. In a car roof, the combination with a sub-structure, of a roofing sheet arranged thereover, a flashing strip, the eaves end of said roofing sheet and said flashing strip being provided respectively with substantially vertically extending parallel overlapping flanges adapted for substantial surface engagement with one another, as and for the purpose set forth.

In testimony whereof I affix my signature.
EDWIN G. FRANCK.
